US0D1067216S

(12) **United States Design Patent** (10) **Patent No.:** **US D1,067,216 S**
(45) **Date of Patent:** **** Mar. 18, 2025**

(54) **EARPIECE**

(71) Applicant: **Apple Inc.**, Cupertino, CA (US)

(72) Inventors: **Robert Brunner**, Glen Ellen, CA (US);
Christopher Kuh, San Francisco, CA (US); **Achille Biteur**, San Francisco, CA (US)

(73) Assignee: **Apple Inc.**, Cupertino, CA (US)

(**) Term: **15 Years**

(21) Appl. No.: **29/952,054**

(22) Filed: **Jul. 12, 2024**

Related U.S. Application Data

(63) Continuation of application No. 29/880,124, filed on Jul. 18, 2023, now Pat. No. Des. 1,035,627, which is a continuation of application No. 29/846,258, filed on Jul. 14, 2022, now Pat. No. Des. 995,489, which is a continuation of application No. 29/812,493, filed on Oct. 21, 2021, now Pat. No. Des. 958,776, which is a continuation of application No. 29/774,949, filed on Mar. 19, 2021, now Pat. No. Des. 934,205, which is a continuation of application No. 29/715,420, filed on Dec. 2, 2019, now Pat. No. Des. 913,994, which is a continuation of application No. 29/654,520, filed on Jun. 25, 2018, now Pat. No. Des. 868,749, which is a continuation of application No. 29/595,719, filed on Mar. 1, 2017, now Pat. No. Des. 821,364, which is a continuation of application No. 29/533,509, filed on Jul. 17, 2015, now Pat. No. Des. 780,721, which is a continuation of application No. 29/490,934, filed on May 15, 2014, now Pat. No. Des. 734,744, and a continuation of application No. 29/490,932, filed on May 15, 2014, now Pat. No. Des. 743,945, and a (Continued)

(57) **CLAIM**

The ornamental design for an earpiece as shown and described.

DESCRIPTION

FIG. 1 is a perspective view of an earpiece showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures show portions of the earpiece that form no part of the claimed design.

1 Claim, 2 Drawing Sheets

Related U.S. Application Data

continuation of application No. 29/490,936, filed on May 15, 2014, now Pat. No. Des. 743,946.
